UNITED STATES PATENT OFFICE

170,572

PHARMACY DISPLAY GLOBE

Farel Hart, St. Petersburg, Fla.

Application July 17, 1953, Serial No. 26,028

Term of patent 3½ years

(Cl. D58—8)

To all whom it may concern:

Be it known that I, Farel Hart, a citizen of the United States, residing at St. Petersburg, in the county of Pinellas and State of Florida, have invented a new, original, and ornamental Design for a Pharmacy Display Globe, of which the following is a specification, reference being had to the accompanying drawings, forming a part hereof.

Figure 1 is a top plan view of a pharmacy display globe, showing my new design;

Figure 2 is a front elevational view;

Figure 3 is a side elevational view;

Figure 4 is a rear elevational view; and

Figure 5 is a bottom plan view.

I claim:

The ornamental design for a pharmacy display globe, as shown.

FAREL HART.
